US00D836464S

(12) **United States Design Patent** (10) **Patent No.:** **US D836,464 S**
Liu et al. (45) **Date of Patent:** **** Dec. 25, 2018**

(54) **WATCH WITH DISPLAY**

(71) Applicant: **Garmin Switzerland GmbH**,
 Schaffhausen (CH)

(72) Inventors: **Kevin Liu**, Kansas City, MO (US);
Nicholas B. Greusel, Overland Park,
 KS (US)

(73) Assignee: **Garmin Switzerland GmbH** (CH)

(**) Term: **15 Years**

(21) Appl. No.: **29/599,722**

(22) Filed: **Apr. 6, 2017**

(51) LOC (11) Cl. **10-02**

(52) U.S. Cl.

USPC **D10/30**

(57) **CLAIM**

The ornamental design for a watch with display, as shown and described.

DESCRIPTION

FIG. 1 is a front perspective view of a watch with display according to the present invention;

FIG. 2 is a rear perspective view of the watch with display;

FIG. 3 is a top view of the watch with display;

FIG. 4 is a front view of the watch with display;

FIG. 5 is a bottom view of the watch with display;

FIG. 6 is a rear view of the watch with display;

FIG. 7 is a left side view of the watch with display; and,

FIG. 8 is a right side view of the watch with display.

The broken lines shown in FIGS. 1 through 8 represent portions of the watch with display that form no part of the claimed design.

1 Claim, 4 Drawing Sheets
